S. W. FUNK

INSECT CATCHER

Filed March 28, 1923

INVENTOR:

Samuel W. Funk

UNITED STATES PATENT OFFICE.

SAMUEL W. FUNK, OF CHARTER OAK, CALIFORNIA.

INSECT CATCHER.

Application filed March 28, 1923. Serial No. 628,304.

To all whom it may concern:

Be it known that I, SAMUEL W. FUNK, a citizen of the United States, residing at Charter Oak, in the county of Los Angeles 5 and State of California, have invented a new and useful Insect Catcher, of which the following is a specification.

This invention relates to devices used for catching or killing insects and especially 10 flies.

One of the objects of this invention is to provide a fly-catching device in form of a gun.

Another object is to provide a device that 15 may be discharged or operated at any angle to a surface on which a fly may be found.

Another object is to provide a device that will discharge or operate very swiftly regardless of the handling of the operator.

20 Another object is to provide a device that is very flexible, thereby avoiding a damaging or marring of furniture or other delicate objects on which flies may be found.

Other objects will appear from the following description and appended claims as 25 well as from the accompanying drawing, in which—

The figure is a perspective illustration of a simple form of the device, partly in section, 30 showing the operating parts of this form.

The device consists mainly of a stationary or handle part or member, and a movable member. In the drawing, the stationary or handle member is provided with a handle- 35 portion 3 and a barrel or tubular portion 4.

The movable member of the device is 40 preferably made of a wire 9, guided in the barrel 4. This movable member is supported and guided for longitudinal movements in relation to the stationary or handle member.

Making the movable member of wire imparts a suitable flexibility to the device, allowing a discharging of the movable member to delicate or well-finished surfaces of furniture or other articles. The front termination of the movable member, on hitting the surface of any article or object, glances off easily without marring or disfiguring 45 such articles, by reason of the flexibility of the wire-form of the movable member. The front end of the wire is preferably terminated in form of a coil 10, to which the wire-screen 11 is secured. The coil 10 im- 50 proves the flexibility of the movable member, so that the screen may fully hit a sur-

face at almost any angle even if the wire 9 moves in a direction straight ahead.

A spring 12 is provided to assure a suitable swiftness in discharging the movable member, regardless of the handling of the operator.

Devices commonly in use for catching flies, such as so-called fly-swatters, depend very much on the swiftness of the operator, 65 to assure a catching of flies.

With the spring 12 inserted, the movable member can be discharged with great swiftness. The movable member is provided with a trigger-like projection 13, by which it may 70 be set into innermost position in relation to the stationary member. The barrel is provided with a slot 14, and an enlarged cut-out 15. The spring 12 is inserted between the front end of the barrel 4 and the trigger-like portion 13 of the movable member.

Pulling the trigger-like portion 13 of the movable member back towards the handle portion 3 of the stationary member, the trigger may be engaged in the enlarged cut-out 15. On pointing the device towards a fly, the trigger-like portion 13 can easily be disengaged from its locked position so that the movable member will be forced outwardly by the spring 12.

85 From the above it will easily be understood that the device may be slightly modified in other ways, and that I do not limit myself to the specific structure shown in the drawing but merely to the principles 90 brought out in the foregoing disclosures and in the appended claims.

Having thus described my invention, I claim:

1. In an insect catcher, a movable member made of wire terminating at one end in the form of a coil and having near the other end a trigger member, a striking gauze being provided on the coil termination on the movable member, the trigger portion 95 being formed integral on the movable member by having the wire bent at about right angles and then bent upon itself to form the trigger portion having the termination bent again to practically align with the 100 main portion of the movable member.

2. In an insect catcher, a housing in form of a barrel having a pistol handle portion at one termination and having a slot extending from a point near the handle portion towards the opposite termination with an enlarged portion to form a locking means 110

within the slot for a cooperating movable member.

3. In an insect catcher, a housing in form of a gun-barrel having a handle portion, 5 the barrel portion having a longitudinal slot extending from a point near the handle portion towards the further end of the barrel, the slot being provided with an enlarged portion to form an engaging shoulder within the slot for a cooperating movable member.

4. In an insect catcher, a housing in form of a gun-barrel having a handle portion, a movable member having a plunger portion slidably disposed in the barrel terminating in a hitting portion of coil form and having a trigger portion, the barrel portion of the housing having a longitudinal slot extending from a point near the 10 handle portion of the housing towards the further end of the barrel to allow the trig- 20

ger portion of the movable member to extend outwardly from the barrel, a spring disposed in the barrel operatively engaged with the movable member so as to force 25 the movable member in one direction in relation to the housing, the slot in the housing being provided with an enlarged portion to form an engaging shoulder for the trigger of the movable member for holding the movable member in retracted position in relation to the housing and adapted to be released so that the spring can force the retracted movable member in longitudinal direction for a striking action. 30

In testimony that I claim the foregoing as my invention I have signed my name in the presence of two subscribing witnesses.

SAMUEL W. FUNK.
